FLUID PRESSURE PRODUCING DEVICE

Owen H. Fowler, Detroit, Mich., assignor to Hydraulic Brake Company, Detroit, Mich., a corporation of California

Application July 11, 1938, Serial No. 218,650

8 Claims. (Cl. 60—54.6)

This invention relates to fluid pressure braking systems, and more particularly to fluid pressure producing devices.

An object of the invention is to provide a fluid pressure producing device operative to increase pressure without increasing the applied operating force.

Another object of the invention is to provide a fluid pressure producing device including a low pressure producing means and a high pressure producing means operative to accomplish a transition from low to high pressure upon attaining a predetermined movement of the low pressure producing means.

A further object of the invention is to provide a fluid pressure producing device including a low pressure producing means and a high pressure producing means operative to dis-associate the low pressure producing means upon effecting a transition from low pressure to high pressure.

Other objects and advantages of the invention will appear from the following description taken in connection with the drawings forming a part of this specification, and in which,

Fig. 1 is a diagrammatical illustration of a fluid pressure braking system embodying the invention;

Fig. 2 is a vertical sectional view of the fluid pressure producing device having associated therewith the reservoir shown partly in elevation and partly broken away;

Fig. 3 is a vertical sectional view illustrating the fluid pressure device on its compression stroke;

Fig. 4 is a sectional view substantially on line 4—4, Fig. 2; and

Fig. 5 is a vertical sectional view illustrating a modification of the fluid pressure producing device.

Referring to the drawings for more specific details of the invention, 10 represents a fluid pressure producing device including a cylinder 12 adapted to be mounted in a fixed position. The cylinder has one end open, and its other end closed as by a head 14 provided with an exhaust port 16 controlled by a two-way valve 18. The open end of the cylinder has rigidly secured thereto a head 20 provided with a concentric orifice 22, and arranged in the wall of the cylinder are spaced ports 24 and 26 known in the art, respectively, as a supply port and a compensating port. The head 20 has a greater diameter than the diameter of the cylinder, hence the head has a portion overhanging the cylinder. A sealing cup 28 seated on the head has a concen-

tric orifice registering with the orifice in the head, and seated on the back of the overhanging portion of the head is a sealing cup 30.

A piston 32 reciprocable in the cylinder 12 seats on the back of the head 20 when in its retracted position. The piston 32 includes a head 34, a reduced body portion 36 providing in conjunction with the wall of the cylinder an annular chamber 38, and a skirt 40 having a concentric recess 42 extended well into the body of the piston. A plurality of spaced passages 44 arranged in the body adjacent the skirt provide communications between the annular chamber 38 and the recess 42, and a plurality of spaced passages 46 in the head of the piston provide communications between the annular chamber 38 and that portion of the cylinder forward of the piston.

A sealing cup 48 on the head of the piston 32 controls the passages 46, and a spring 50 interposed between the sealing cup 48 and the two-way valve 18 serves to retain the cup and valve against displacement and also to return the piston to its retracted position.

25 A cylinder 52 reciprocable on the fixed cylinder 12 has one end closed as by a head 54 and its other end open. The head 54 has suitably mounted therein a thrust pin 56 extended into the cylinder with its free end in the recess 42 30 of the piston 32. The head of the thrust pin has a recess 58, the purpose of which will hereinafter appear, and a spring 60 interposed between the head 54 and the sealing cup 28 serves to retain the cup against displacement and also 35 to return the cylinder 52 to its retracted position.

In the wall of the cylinder 52 is a supply port 62 communicating with a suitable reservoir 64 mounted on the cylinder. This supply port is 40 arranged immediately forward of the sealing cup 28 and is adapted to be closed by the cup upon the initial movement of the cylinder 52 on its compression stroke. The open end of the cylinder 52 extends over the cylinder 12 beyond the ports 24 and 26, and is closed by a ring 66 so as to provide an annular chamber 68 communicating with the cylinder 12 by way of the ports 24 and 26. The ring 66 is suitably secured to the open end of the cylinder 52 and slidably 45 embraces the cylinder 12. A sealing cup 70 seated on the ring 66 inhibits seepage of fluid from the chamber 68, and a spring 72 interposed between the sealing cup 70 and the sealing cup 30 seated on the overhanging portion of the head 50 55 20 retains these cups in position and also deter-

mines the retracted position of the cylinder 52 wherein the cylinder 52 is balanced between the springs 60 and 72. The cylinder 52 also has in its wall a port 74 communicating with the annular chamber 68 and normally closed as by a bleeder screw 76.

A fluid pressure delivery pipe or conduit 78 connected to the discharge port 16 of the cylinder 12 has branches connected respectively to fluid pressure actuated motors 80, preferably arranged in pairs, one pair for actuating the brakes associated with the front wheels of the vehicle, and another pair for actuating the brakes associated with the rear wheels of the vehicle.

The brakes, which may be of any desirable type, preferably include a fixed support or backing plate 82 adapted to be secured to an axle or to an axle housing, a rotatable drum 84 associated with the backing plate adapted to be secured to a wheel, a pair of friction elements or shoes 86 pivoted on the backing plate for cooperation with the drum, a retractile spring 88 connecting the shoes, and a motor corresponding to the motors 80 mounted on the backing plate between the shoes and operative to actuate the shoes into engagement with the drum against the resistance of the retractile spring.

The socket 58 in the head of the thrust pin 56 receives one end of a thrust rod 90, the other end of which is connected by a clevis 92 to a foot pedal lever 94 rockable on a stub shaft 96 and connected by a retractile spring 98 to a fixed support 100.

In a normal operation, upon depressing the foot pedal lever 94, force is transmitted therefrom through the rod 90 to the cylinder 52, resulting in movement of the cylinder. During the initial movement of the cylinder 52, the sealing cup 28 on the head of the head 20 closes the port 62 providing the communication between the cylinder 52 and the reservoir 62, and thereafter as the cylinder 52 advances the fluid in the cylinder 52 is displaced therefrom through the orifice 22 in the head 20, the recess 42 and passages 44 in the reciprocable piston 32 into the annular chamber 38, thence through the passages 46 in the head of the reciprocable piston, past the sealing cup 48, into that portion of the fixed cylinder 12 forward of the reciprocable piston, thence past the two-way valve 18, through the discharge port 16 and fluid pressure pipe or conduit 78 and its respective branches into the fluid pressure actuated motors 80, causing energization of the motors and resulting in actuation of the shoes 86 into engagement with the drums 84 against the resistance of the retractile springs 88.

During this operation, the cylinder 52 has traveled sufficiently to seat the thrust pin 56 in the recess 42 in the reciprocable piston 32, and thereafter, as the cylinder 52 advances, the reciprocable piston is moved on its compression stroke. During the initial movement of this piston on its compression stroke, the cup 48 closes the port 26, whereupon the pressure on the fluid is transferred from the large cylinder 52 to the small cylinder 12, and thereafter the fluid in the large cylinder is displaced therefrom through the orifice 22 in the head 20, the recess 42 and passages 44 in the reciprocable piston 32 into the annular chamber 38, thence through the port 24 into the annular chamber 68, thence through the port 62 into the reservoir 64, and the fluid in the cylinder 12 forward of the reciprocable piston is displaced therefrom past the two-way valve 18, through the discharge port 16 and fluid pressure

75 delivery pipe 78 and its respective branches into the fluid pressure actuated motors 80, causing further energization of the motors 80, resulting in further actuation of the shoes 86 into engagement with the drums 84 against the resistance of the drums so as to effectively retard rotation of the retractile springs.

Upon the conclusion of a braking operation, the foot pedal lever 94 is released and returns to its retracted position under the influence of the retractile spring 98. This results in release of the cylinder 52 and return thereof to its retracted position under the influence of the spring 60 wherein the cylinder is balanced between the springs 60 and 72.

15 During this operation the reciprocable piston 32 is returned to its retracted position under the influence of the retractile spring 50, and as the piston 32 returns to its retracted position a partial vacuum is created in that portion of the cylinder 12 forward of the reciprocable piston 32. This results in drawing fluid from the reservoir through the port 62 into the cylinder 52, thence through the orifice 22 in the head 20, the recess 42 and passages 44 in the reciprocable piston 32 into the annular chamber 38, thence through the passages 46 in the head of the reciprocable piston, past the sealing cup 48 into that portion of the cylinder 12, completely filling this cylinder.

20 30 Concomitantly with this operation fluid is returning to the cylinder 12 from the fluid pressure actuated motors 80 and the fluid pressure delivery pipes connecting the motors to the cylinder 12. This results in the cylinder 12 receiving a quantity of fluid in excess of its capacity, and this excess quantity of fluid is displaced from the cylinder 12, through the port 26, into the annular chamber 68, thence through the port 24 into the annular chamber 38, thence through passage 54, recess 42 in the reciprocable head and orifice 22 in the piston 20 into cylinder 52, thence by way of port 62 into the reservoir.

25 35 40 A modification of the fluid pressure producing device is illustrated in Fig. 5. In this embodiment of the invention a cylinder 102 adapted to be mounted in an upright position has its lower end closed as by a head 104 provided with a discharge port 106 controlled by a two-way valve 108. The upper end of the cylinder has secured thereto a head 110 provided with a concentric orifice 112, and arranged in the wall of the cylinder are spaced ports 114 and 116. The head 110 has a greater diameter than the diameter of the cylinder so that the perimeter of the head overhangs the cylinder. A sealing cup 118 seated on the head 110 has a concentric opening registering with the orifice 112 in the head, and seated on the back of the overhanging portion of the head is a sealing cup 120.

45 50 55 60 65 70 75 A piston 122 reciprocable in the cylinder 102 seats on the back of the head 110. The piston 122 includes a head 124, a reduced body portion 126 providing in conjunction with the cylinder an annular chamber 128, and a skirt 130 having a concentric recess 132 extending well into the body of the cylinder, and the body has a plurality of spaced passages 134 arranged therein adjacent the skirt providing communications between the annular passage 128 and the recess 132. The head of the piston 126 has a plurality of spaced passages 136 therethrough providing communications between the annular passage 128 and that portion of the cylinder 102 forward of the piston. A sealing cup 138 seated on the head of the piston 126 controls the passages 136, and a spring 140

interposed between the sealing cup 138 and the two-way valve 108 serves to retain the cup and valve against displacement and also to return the piston to its retracted position.

A cylinder 142 reciprocable on the cylinder 102 has thereon a concentric reservoir 144 communicating with the cylinder as by way of a port 146 arranged in the wall of the cylinder immediately forward of the sealing cup 118 on the head 110. The cylinder 142 is closed at its upper end by a head 148 having mounted therein a thrust pin 150 extending downwardly into the recess 132 of the piston 122, and a spring 152 interposed between the head 148 and the sealing cup 118 serves to retain the cup against displacement and also to return the cylinder 142 to its retracted position. The lower end of the cylinder is closed by a ring 154 suitably secured thereto and slidably embracing the cylinder 102. The ring supports a sealing cup 156, and a spring 158 interposed between the sealing cup 156 and the sealing cup 120 serves to retain these cups against displacement and also to determine the retracted position of the cylinder 142.

Because of the increased diameter of the head 110, the walls of the respective cylinders 102 and 142 are in spaced relation to one another. This provides, between the back of the head 110 and the ring 150, an annular chamber 160 communicating with the cylinder 102 by way of the ports 114 and 116.

The reservoir 144 is closed by a cover plate 162 having a plurality of spaced openings 164 for venting the reservoir to the atmosphere. The cover plate is held against displacement by a head 166 on the thrust pin 150, and the head 166 has a socket 168 for the reception of a thrust pin 170.

The operation of the fluid pressure producing device illustrated in the modification is identical to that of the preferred form of the invention. The only difference between the two devices is to be found in the structure of the reservoirs, one being adapted for mounting in substantially horizontal position, and the other adapted for mounting in substantially vertical position. Hence it is not deemed necessary to repeat the operation.

Although this invention has been described in connection with certain specific embodiments, the principles involved are susceptible of numerous other applications that will readily occur to persons skilled in the art. The invention is, therefore, to be limited only by the scope of the appended claims.

Having thus described the various features of the invention, what I claim as new and desire to secure by Letters Patent is:

1. A fluid pressure producing device comprising a small fixed cylinder, a large movable cylinder telescoping the small cylinder, a reservoir communicating with the large cylinder, a variable chamber between the peripheral walls of the cylinders continuously communicating with the small cylinder through its peripheral wall and adapted to communicate with the reservoir after a predetermined movement of the large cylinder, an orificed head on the inner end of the small cylinder, a reciprocable piston in the small cylinder, and means carried by the large cylinder for advancing the reciprocable piston.

2. A fluid pressure producing device comprising a small fixed cylinder, a relatively large movable cylinder telescoping the small cylinder, a reservoir communicating with the large cylinder, a chamber between the peripheral walls of the cylinders continuously communicating with

the small cylinder through its peripheral wall and adapted to communicate with the reservoir after a predetermined movement of the large cylinder, an orificed head on the inner end of the small cylinder, a reciprocable piston in the small cylinder, means for by-passing fluid past the reciprocable piston, and means carried by the large cylinder for advancing the reciprocable piston.

3. A fluid pressure producing device comprising a small cylinder closed at one end by a head having a discharge port and open at its other end, an orificed head on the open end having a larger diameter than that of the cylinder, a reciprocable piston in the small cylinder, a relatively large cylinder closed at one end and open at its other end telescoping the small cylinder and providing in conjunction therewith a variable chamber communicating with the small cylinder, a ring on the open end of the large cylinder slidably embracing the small cylinder and providing a closure for the variable chamber, and a pin in the head of the large cylinder extended through the orificed head and adapted to engage the reciprocable piston.

4. A fluid pressure producing device comprising a small cylinder closed at one end by a head having a discharge port and open at its other end, an orificed head on the open end, a reciprocable piston in the cylinder, a relatively large cylinder closed at one end and open at its other end telescoping the small cylinder and reciprocable on the orificed head, a ring on the open end of the large cylinder slidably embracing the small cylinder, a reservoir communicating with the large cylinder forward of the orificed head, means for balancing the large cylinder on the orificed head, and a thrust pin carried by the large cylinder for advancing the reciprocable piston.

5. A fluid pressure producing device comprising a small cylinder closed at one end by a head having a discharge port and open at its other end, an orificed head on the open end, a reciprocable piston in the cylinder normally seated on the back of the orificed head, a relatively large cylinder closed at one end and open at its other end reciprocable on the orificed head, a reservoir communicating with the large cylinder, a ring on the open end of the large cylinder slidably embracing the small cylinder, a variable chamber between the cylinders communicating with the small chamber and adapted to communicate with the reservoir after a predetermined movement of the large cylinder, a spring interposed between the orificed head and the head of the large cylinder, a spring interposed between the ring and the back of the orificed head, and a thrust pin on the head of the large cylinder for advancing the reciprocable piston.

6. A fluid pressure producing device comprising a small cylinder closed at one end by a head having a discharge port and open at its other end, an orificed head on the open end having a diameter greater than the diameter of the small cylinder, a reciprocable piston in the small cylinder, means for by-passing fluid past the reciprocable piston, a relatively large cylinder reciprocable on the orificed head having one end closed and its other end open, a reservoir communicating with the large cylinder forward of the orificed head, a ring on the open end of the large cylinder slidably embracing the small cylinder and providing a closure for the large cylinder, a variable chamber between the cylinders communicating with the small cylinder and adapted to communicate with the reservoir after a predetermined movement of the large cylinder,

means for balancing the large cylinder on the orificed head, and a thrust pin on the head of the large cylinder extending through the orificed head and adapted to engage and advance the reciprocable piston after a predetermined movement of the large cylinder.

7. A fluid pressure producing device comprising a small cylinder closed at one end by a head having a discharge port and open at its other end, means for mounting the small cylinder in a fixed position, a two-way valve controlling the discharge port, an orificed head on the open end of the small cylinder having a diameter greater than the small cylinder, a reciprocable piston in the small cylinder, means for by-passing fluid past the reciprocable piston, a sealing cup on the reciprocable piston, a spring interposed between the sealing cup and the two-way valve urging the reciprocable piston to seat on the back of the orificed head, a relatively large cylinder reciprocable on the orificed head having one end closed by a head and its other end open, a sealing cup on the orificed head, a spring interposed between the cup on the orificed head and the head of the large cylinder, a reservoir communicating with the large cylinder immediately forward of the sealing cup on the orificed head, a ring on the open end of the large cylinder slidably embracing the small

cylinder, a sealing cup on the ring, a sealing cup on the back of the orificed head and a spring interposed between the cups, a variable chamber between the cylinders communicating with the 5 small cylinder and adapted to communicate with the reservoir after a predetermined movement of the large cylinder, and a thrust pin on the head of the large cylinder extended through the orificed head and adapted to engage and advance the reciprocable piston.

8. A fluid pressure producing device comprising telescopic cylinders closed at their outer ends and open at their inner ends, the closed end of the inner cylinder having a discharge port, an orificed head on the open end of the inner cylinder, a ring on the open end of the outer cylinder slidably embracing the inner cylinder, a reservoir communicating with the outer cylinder forward of the orificed head, a variable chamber between the cylinders back of the orificed head communicating with the small cylinder and adapted to communicate with the reservoir after a predetermined movement of the outer cylinder, a piston reciprocable in the inner cylinder, means for bypassing fluid past the reciprocable piston, and means carried by the large cylinder for advancing the reciprocable piston.

OWEN H. FOWLER.
